Filed May 4, 1972, Ser. No. 250,485

Term of patent 14 years

Int. Cl. D7—01

U.S. Cl. D7—9

FIG. 1 is a perspective view of a mug or similar article showing my design;

FIG. 2 is a side elevation view;

FIG. 3 is a bottom plan view; and

FIG. 4 is a sectional view taken along line 4—4 of FIG. 2.

As indicated in the drawings, the bottom portion of the mug is made of translucent material so that the liquid between the inner and outer shell of the mug can be seen.

I claim:

The ornamental design for a mug or similar article, as shown and described.
